US0D1068874S

(12) **United States Design Patent** (10) **Patent No.:** **US D1,068,874 S**
(45) **Date of Patent:** **** Apr. 1, 2025**

(54) **EXTRUDER PORTION OF A PRINT HEAD**

(71) Applicant: **Stratasys, Inc.**, Eden Prairie, MN (US)

(72) Inventors: **Ross Michalkiewicz**, Minneapolis, MN (US); **Dang Yang**, Champlin, MN (US); **Brett Johnson**, Roseville, MN (US)

(73) Assignee: **STRATASYS, INC.**, Eden Prairie, MN (US)

(**) Term: **15 Years**

(21) Appl. No.: **29/860,764**

(22) Filed: **Nov. 22, 2022**

(51) **LOC (15) Cl.** **15-09**

(52) **U.S. Cl.**

USPC **D15/122; D15/138**

(58) **Field of Classification Search**

USPC D15/122, 138, 141, 199; D18/50, 53, 56
CPC B29C 64/00; B29C 64/20; B29C 64/25;

B29C 64/118; B29C 64/209; B33Y 30/00

(57) **CLAIM**

The ornamental design for an extruder portion of a print head as shown and described.

DESCRIPTION

FIG. 1 is a perspective view of an extruder portion of a print head showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings are included for purposes of illustrating portions of the extruder portion of a print head and form no part of the claimed design.

1 Claim, 7 Drawing Sheets
